CLAIM

The ornamental design for an EAS tag, as shown and described.

DESCRIPTION

FIG. 1 is a 3/4 top perspective view of an EAS tag embodying the ornamental design of this invention;

FIG. 2 is a 3/4 bottom perspective view thereof;

FIG. 3 is a top plan view thereof;

FIG. 4 is a bottom plan view thereof;

FIG. 5 is a right side elevation thereof;

FIG. 6 is a left side elevation thereof;

FIG. 7 is a right end elevation thereof; and,

FIG. 8 is a left end elevation thereof.

In the drawings, the broken lines depict environmental subject matter only and form no part of the claimed design.
